BOILER-TUBE CLEANER

Harrison L. Staley, Martinsville, Ind.

Application July 20, 1933, Serial No. 681,257

8 Claims. (Cl. 15—104.14)

This invention relates to improvements in a class of tube cleaners adapted to be rotated at high speed, and having a rotary head upon which are slidably mounted centrifugally acting wings 5 which carry thereon rotatable toothed cutters for removing scale or incrustation from the inner walls of boiler tubes.

More specific objects of my invention are, first, to provide a cleaner for either straight or curved tubes, in which great flexibility is introduced by novel arrangement of parts so that bends in tubes can be negotiated without lessening the cutting action; second, to provide a cleaner with wings to slide radially and swing freely; third, to provide a cleaner of this type with cutters of new design in which the tendency of the teeth to strike repeatedly at the same point is eliminated.

My invention will be best understood by reference to the accompanying drawing, in which Figure 1 is a side elevation of the tool with one wing expanded indicating the position it assumes as it emerges from the tube; Figure 2 is a sectional front view of Figure 1 on line 2, 2; Figure 3 is a view in perspective of the body member; Figure 4 is a view in perspective of the slidable wing; Figure 5 is a front view of the cylindrically shaped cutters used; Figure 6 is a side elevation of the same cutter; Figure 7 is a front view of the cone shaped cutter which is placed in the most forward position of the cleaner; Figure 8 is a side elevation of the same device.

The numeral 1 designates the body of my invention, which consists of a longitudinally extending shaft 3, having a plurality of rectangularly shaped arms 4 projecting radially near one end of the body thereof, the other end being provided with screw connection 16 for attaching a driving mechanism to the device. The central section of shaft 3 is reduced longitudinally to make the remaining portion conform to the thickness of said projecting arms, the object being to provide an abutting member for the rearward end of slidable wing 5 when the cleaner passes through the end of the tube.

45 A radially extending recess 7 is provided in projecting arm 4 for the introduction of pin 8, said pin arranged to retain the cleaner in an assembled position. Recess 7 should be located behind the center of gravity of assembled wing 5 so that when the cleaner passes through the tube, the action of centrifugal force upon center of weight forward of recess 7 will cause the rearward end of the wing to move inwardly behind collar 22, permitting the cleaner to be easily drawn back into the tube again. A recess 6 should be cut into the shaft portion for cutters 12 so as to permit a closer nesting of the head when in closed position. I prefer that a shoulder 26 be located forward of threads 16 to provide a stop for collar 22.

Wings 5 of my preferred form being identical, I shall describe one only. In outline it is rectangular, with a longitudinally extending groove 9 cut throughout its lower portion. A rectangular slot 10 is provided through the forward portion of said wing to coincide with groove 9 and arranged to movably engage radially extending arm 4. Slot 10 should be large enough to permit the wing to slide outwardly and swing freely on said projecting arm 4. Rearwardly of slot 10, 10 a transverse groove 11 is made in the wing for the introduction of cutters 12. Said cutters are retained in position by a headed bolt 13 which is introduced in hole 14 and secured in the wing by means of a threaded section engaging threads 15 15. Behind the head of bolt 13 are rotatably mounted two cutters 17 and 18, the forward cutter 18 being conical in shape.

Hole 23 provides housing facilities for pin 8. Said hole is bored partly through the lower wall 20 of hole 14 so that when pin 8 which has a central transverse groove therein, is placed within its receiving hole 23, bolt 13 will pass through the groove thereof and retain the pin in position. It is necessary that bolt 13, be located at one 25 side of the radial line of movement of said wing, and I prefer that it be placed forwardly of projecting arm 4 as related to its direction of rotation to greatly increase the cutting action.

It is obvious that the scale on the wall of the 30 boiler tube resists the forward movement of cutters 12, 17 and 18 and that this resisting force is opposite to the direction of the motion of said cutters at the point of contact of the aforesaid cutters and said tube wall. In other words this 35 force is tangent to the surface of the tube at the point of contact and opposite to the direction of travel of said cutters. It is well understood of course, that this resisting force is transmitted from said cutters to the wing 5 through bolt 13. 40

Since wing 5 is free to slide on arm 4, the only driving force which frame 1 may transmit to said wing, is a force perpendicular to the surface of arm 4 of said frame. Now if bolt 13, which is in reality the center of cutters 12, 17 and 18 is 45 placed on the line of motion of wing 5, the resisting force on said cutters and arm will be exactly opposite in direction to the driving force on arm 4.

However, if bolt 13, and therefore the center 50 of said cutters, is placed to one side of the line of motion of wing 5, the resisting force on said cutter and arm is applied at an angle to the driving force on said arm. The resultant force set up by the action of the resisting force and the 55 driving force will be perpendicular to the tube wall, and will be against the tube wall if cutters are in front of arm 4 of frame 1, or away from the tube wall if said cutters are behind arm 4 of said frame.

It will thus be seen that by placing bolt 13 to one side of the line of motion of wing 5 makes possible as desired, an increase or decrease of cutting pressure on the scale within the tube. 5 This increase or decrease of cutting pressure is entirely separate from, and in addition to the centrifugal force on said wing.

Cutters 12 and 18 used on this tube cleaner are of an improved design. Instead of having 10 the points of all the teeth 19 regularly spaced at any cross section perpendicular to the axis of rotation, the teeth are formed by the same angular cutter but cut at unequal tooth depths to make a difference in circular pitch of the teeth so as 15 to eliminate the tendency of the teeth to strike repeatedly at the same point like a knurling tool. In my preferred design of cutters, the base line 20 of the teeth is slightly eccentric to the centrally located hole 21, which causes the points of 20 the teeth to have unequal spaces between them. The distance from b to b' is greater than the distance from c to c' with a gradation of spaces between these two extremes.

In operation, the cleaner is attached to a prime 25 mover and rotated at high speed. This rotation causes wing 5 to move outwardly by centrifugal action until cutters 12, 17 and 18 come in contact with the scale. Should cutter 18 strike a heavy 30 piece of scale the forward portion of wing 5 will move inwardly and relieve arm 4 of undue strain. Also should there be a pocket in the tube due to 35 a heat blister, wing 5 possesses such flexibility of movement that the cutters thereon will reach in and remove the scale therein. By permitting wings 5 to swing freely on radially extending arms 4, bends in tubes can be negotiated with great 40 effectiveness and speed in cleaning because the forward and rear cutters are kept in constant contact with the tube and with all strain removed from the cleaner.

Having fully described my invention I claim as new:

1. A tube cleaner having a revoluble cutter head which comprises a body with radially projecting arms thereon, wings mounted on said 45 projecting arms and arranged to slide outwardly, a longitudinally extending bolt secured in each of said wings to one side of the radial line of movement of said wing, rotary cutters mounted 50 on said bolt and means to limit the outward movement of said wing on said arm.

2. A tube cleaner having a revoluble cutter head, comprising a body with radially projecting 55 rectangularly shaped arms thereon, wings having a rectangular radial slot therethrough engaging said projecting arms and arranged to slide outwardly, a longitudinally extending bolt carrying rotatable cutters secured in each of said wing to one side of the radial line of movement 60 of said wings and means to limit the outward movement of said wing on said arm.

3. A tube cleaner having a revoluble cutter head, comprising a body with radially projecting arms thereon, each arm being provided with a 65 radially extending recess therein, a wing mounted on each of the projecting arms and arranged to slide outwardly, a longitudinally extending bolt carrying rotatable toothed cutters secured in each of said wings to one side of the radial line of 70 movement of said wing and means to limit the outward movement of said wing, said means consisting of a pin secured in said wing transversely to the axis of rotation and engaging the radially extending recess in said projecting arm.

4. A tube cleaner having a revoluble cutter

head, comprising a body with radially projecting arms thereon, each arm being provided with a radially extending recess therein, wings mounted on said projecting arms and arranged to slide outwardly thereon, a longitudinally extending bolt carrying rotatable toothed cutters secured in each of said wing to one side of the radial line of movement of said wing, a pin set transversely to the axis of rotation in said wing, the end of which engages the radially extending recess in said projecting arm and means to hold 10 lockingly said pin in said wing. 5

5. A tube cleaner having a revoluble cutter head, comprising a body with radially projecting arms thereon, each arm being provided with a radially extending recess therein, a wing mounted on each of said projecting arms and arranged to slide outwardly thereon, a longitudinally extending bolt carrying rotatable toothed cutters secured in each of said wing to one side of the radial line of movement of said wing, a pin set in said wing transversely to the axis of rotation of said wing, the end of which engages the radially extending recess in said projecting arm and means to hold lockingly said pin in said wing. 25

6. A tube cleaner having a revoluble cutter head, comprising a body with radially projecting arms thereon, wings provided with a radial slot therethrough and radially extending groove rearwardly of said radial slot, said wing being slidably mounted on said projecting arm, a longitudinally extending bolt secured in each of said wings to one side of the radial line of movement of said wing, cutters rotatably mounted on bolts forwardly of said wing and in the radially extending groove 35 in said wing and means to limit the outward movement of said wing on said projecting arm.

7. A tube cleaner having a revoluble cutter head, comprising a body having radially projecting rectangularly shaped arms thereon, each arm being provided with a radially extending recess therein, wings slidably mounted on said projecting arms, each wing being provided with a radial slot therethrough and a radially extending groove rearwardly of said radial slot, a longitudinally extending bolt secured in each of said wings to one side of the radial line of movement of said wing, rotatable toothed cutters mounted on said bolt forwardly of said wing and rearwardly in the radially extending groove in said wing, 50 and means to limit the outward movement of said wing on said projecting arm, said means consisting of a pin set transversely in said wing to its axis of rotation and engaging the radial recess in said projecting arm. 55

8. A tube cleaner having a revoluble cutter head, comprising a longitudinally extending body having radially projecting rectangularly shaped arms thereon, each arm having a radially extending recess therein, wings provided with a radial slot therethrough and a radially extending groove rearwardly of said radial slot and arranged to slide outwardly and swing freely on said arm, a longitudinally extending bolt removably secured in each of said wings to one side of the radial line of movement of said wing, rotatable toothed cutters mounted on said bolt forwardly of said wing and rearwardly in the radially extending groove in said wing, a pin set transversely to the axis of rotation in said wing to engage the radial recess in said projecting arm, said pin having a circular groove engaging the threaded bolt in said wing substantially as described. 70
